UNITED STATES PATENT OFFICE.

MARTIN OSTROWIECKI, OF CHICAGO, ILLINOIS.

DESIGN FOR A PICTURE FRAME.

Application filed July 23, 1924. Serial No. 10,231. Term of patent 7 years.

To all whom it may concern:

Be it known that I, MARTIN OSTROWIECKI, a citizen of the United States of America, residing at Chicago, in the county of Cook and State of Illinois, have invented a new, original, and ornamental Design for Picture Frame, of which the following is a specification, reference being had to the accompanying drawing, forming a part hereof.

The figure is a front plan view showing my new, original and ornamental design for picture frame.

I claim:

The ornamental design for a picture frame as shown.

MARTIN OSTROWIECKI.

Witnesses:

WENZEL J. LOVE,

THADAUS LOVE.
